(57) **CLAIM**

The ornamental design for a hairbrush, as shown and described.

DESCRIPTION

Related U.S. Application Data

(63) Continuation of application No. 29/521,112, filed on Mar. 19, 2015, now Pat. No. Des. 803,574.

FIG. 1 is a front view of a first embodiment of a hairbrush showing the new design;

(51) **LOC (13) Cl.** **04-01**

FIG. 2 is a back view thereof;

(52) **U.S. Cl.**

FIG. 3 is a right side view thereof;

USPC **D4/130**

FIG. 4 is a left side view thereof;

(58) **Field of Classification Search**

FIG. 5 is a top view thereof;

USPC D4/130, 132–134, 136, 129, 121, 138,

FIG. 6 is a bottom view thereof;

D4/199; D24/200, 214, 211; D28/63;

FIG. 7 is a perspective view thereof;

15/159.1, 160, 186–188, 207.2, DIG. 5,

FIG. 8 is a front view of the hairbrush according to a second embodiment;

15/143.1; 132/120, 313, 901, 121, 137,

FIG. 9 is a back view thereof;

132/142, 161; 401/28; 601/109, 136,

FIG. 10 is a right side view thereof;

601/137; 119/600, 612, 615, 632, 652,

FIG. 11 is a left side view thereof;

119/664

FIG. 12 is a top view thereof;

CPC A46B 3/00; A46B 3/20; A46B 3/22; A46B

FIG. 13 is a bottom view thereof, and,

5/00; A46B 5/02; A46B 5/021; A46B

FIG. 14 is a perspective view thereof.

5/026; A46B 7/00; A46B 7/02; A46B

The broken lines immediately adjacent to the shaded areas, represent the bounds of the claimed design while all other broken lines are directed to environment and are for illustrative purposes only; the broken lines form no part of the claimed design.

9/00; A46B 9/02; A46B 9/023; A46B

(Continued)

The portions between the pairs of closely adjacent, spaced jagged dash-dot broken lines in the drawings are broken away to indicate no particular length or width, and such pairs of jagged, broken lines themselves form no part of the claimed design. The materials that may be visible between the jagged lines have been removed for clarity.

1 Claim, 10 Drawing Sheets
